UNITED STATES PATENT OFFICE.

JAMES P. WITHEROW, OF PITTSBURG, PENNSYLVANIA.

APPLIANCE FOR REGULATING THE BLAST-PRESSURE OF CONVERTERS.

SPECIFICATION forming part of Letters Patent No. 317,263, dated May 5, 1885.

Application filed March 12, 1885. (No model.)

To all whom it may concern:

Be it known that I, JAMES P. WITHEROW, of Pittsburgh, in the county of Allegheny and State of Pennsylvania, have invented a new

5 and useful Improved Appliance for Regulating the Blast-Pressure of Converters; and I do hereby declare the following to be a full, clear, and exact description thereof.

In fixed converters for treating molten metal 10 the tuyeres are usually arranged in the sides below the metal-line, and in such case it is necessary to make provision for preventing the metal from entering the tuyeres, as it would then be liable to chill and stop up the 15 tuyere-holes, necessitating frequent renewals of the tuyeres. For this purpose tuyere-stoppers and valves have been used, and also a single valve arranged in the blast-main, which was used to reduce the pneumatic pressure to 20 the degree necessary to sustain the ferro-static pressure at the mouths of the tuyeres when the active treatment of the charge was not going on.

There are objections to each of these methods; and my improvement consists in appliances for regulating the pressure at the tuyere-mouths during the operation of the converter by varying the speed of the blast-engine. By my invention I bring the blast-engine directly 25 under the management of the blower, (the person in charge of the converter,) and thus put the entire operation under one control, insuring greater certainty in the nice operations of the converter. The process in the 30 converter is so rapid and the effects produced so varying that great precision and nicety in details—such as the pressure of the blast, length of blow, &c.—are of the greatest importance, and all devices and expedients which 35 tend thereto are of moment.

To enable others skilled in the art to make use of my invention, I will now describe it by reference to the accompanying drawing, which is a view showing the blast-engine and controlling devices in elevation and the converter 45 in vertical section.

The blast-engine *a* is of the usual construction, and communicates with the converter *b* by a blast-main, *c*.

50 Situate at any convenient point in the blast-main is a relief-valve, *d*, which, in case the pressure of the blast should exceed that which

is desired for the converter, will open and permit the escape of a sufficient quantity of air to relieve the pressure and reduce it to the 55 desired degree.

The blast-main is also fitted with a slide-valve, *e*, for the purpose of shutting off the blast to the converter in case of emergency, which is operated by a gear-wheel, *e'*, mounted 60 on the shaft, which carries a pulley, *e''*, which in turn is operated by a belt, *e'*, extending to a hand-wheel, *e''*. Any other suitable devices may be used for this purpose.

Mounted in suitable bearings is a shaft or 65 spindle, *f*, provided with a hand-wheel, *f'*, at the end nearest the converter *b*. This spindle is connected with the stem *g* of the cut-off valve of the blast-engine by means of the shafting and gearing *h*, or other suitable power-connection devices, whereby the admission of steam to the cylinder of the engine may be controlled by the operation of the hand-wheel *f'*. The hand-wheel *f'*, or other means of manipulation, is arranged at or near the converter *b*, so 70 as to be under the control of the blower. In this way the management of the blast-engine and the operations of the converter are put under a single control, whereby precision and uniformity are insured, and the danger of the 75 loss and trouble from confusion of orders or misunderstanding between the managers of these two important parts of the plant are avoided. This arrangement has the further advantage of dispensing with the services of 80 an engineer in the engine-house, if desired. By the manipulation of the hand-wheel *f'* the blower is enabled to regulate the blast both as to volume and pressure at will, and when it is desired to stop the blow he can do it instantly by closing the gate-valve *e*. This latter operation does not necessarily involve the 85 stopping of the engine, because as soon as the gate-valve is closed the relief-valve *d* will be opened by the pressure and permit the blast 90 to escape into the air.

By my improvement, in which I extend the functions of necessary parts, I am enabled to do away with all valves, stoppers, and other devices for controlling the pressure of the 100 blast at the tuyeres, and to accomplish the same result in a speedy and efficient manner by varying the speed of the blast-engine. The whole volume of the blast being directly un-

der the control of the blower, the operations of the converter are not liable to be injuriously affected by any defects which may occur in separate valves at one or more tuyeres while 5 the others are in good working order. The blast being equal at the tuyeres, they are not liable to get out of order or stop up, and the charge of molten metal in the converter will be treated much more uniformly than in the 10 case of separate valves or stoppers for the tuyeres.

I do not herein claim the method of regulating the pressure of the blast at the tuyeres by varying the speed of the blast-engine, for 15 the reason that such method forms the subject-matter of another application; nor do I herein claim a slide or gate valve in connection with the main blast for regulating the volume and pressure of the blast in the 20 converter, as such construction forms the subject-matter of another application.

I have described a line of shafting and gearing as the means of operating the cut-off valve of the engine from the converter; but I do not 25 limit myself thereto, as any other form of

power-connections having a positive motion may be used, and is the equivalent for that purpose of shafting and gearing illustrated.

What I claim as my invention, and desire to secure by Letters Patent, is—

1. The combination of a converter having its tuyeres arranged below the metal-line with a blast-engine and its cut-off valve, blast-connections between said engine and converter, and power-connections for operating said cut-off valve from the vicinity of the converter, substantially as and for the purposes described. 30

2. The combination of a blast-engine and its cut-off with a converter, blast-connections between the engine and converter, a blast-closing valve arranged in such connections, and power-connections for operating the cut-off from the converter, substantially as and for the purposes described. 35

In testimony whereof I have hereunto set 40 my hand, this 9th day of March, A. D. 1885.

JAMES P. WITHEROW.
